UNITED STATES PATENT OFFICE.

AXEL G. J. RAPP, OF CHICAGO, ILLINOIS, ASSIGNOR TO LINK-BELT COMPANY, OF CHICAGO, ILLINOIS, A CORPORATION OF ILLINOIS.

CRUSHING-MACHINE.

1,185,937.

Specification of Letters Patent.

Patented June 6, 1916.

Application filed March 29, 1915. Serial No. 17,578.

To all whom it may concern:

Be it known that I, AXEL G. J. RAPP, a citizen of the United States, residing at Chicago, in the county of Cook and State 5 of Illinois, have invented a certain new and useful Improvement in Crushing-Machines, of which the following is a specification.

My invention relates to improvements in crushing machines and has particular relation to that type of machine wherein the material to be reduced is crushed between the concave fixed plate and the rotating roll and wherein the crushing is accomplished by teeth or knobs on the roll and wherein 15 the material is drawn down into the aperture between the concaves and the roll by a series of projecting spikes or teeth.

One object of my invention is to provide means for easily and conveniently renewing these teeth or spikes without dismounting the machine.

Another object is to provide means for feeding the material to these teeth or spikes to prevent clogging of the machine.

Other objects of my invention will appear in the specification.

My invention is, therefore, illustrated more or less diagrammatically in the accompanying drawings, wherein—

Figure 1 is a side elevation of a crushing machine; Fig. 2 is a detail section through a crushing zone; Fig. 3 is a section on an enlarged scale through the crushing drum showing the means for removably attaching 30 one of the teeth; Fig. 4 is a detail plan view on an enlarged scale of one of the tooth or cutter holding levers; Fig. 5 is a perspective of the surface of one of the concaves; Fig. 6 is a section on Fig. 5; and Fig. 7 is a detail section through the crushing concave along the line parallel with the axis 35 of rotation of the drum.

Like parts are indicated by like letters throughout the several figures.

A is a main frame. A¹ a hopper carried thereby.

A² a concave. It is held in position in the main frame by the shafts A³, A⁴.

A⁵ is the crushing drum mounted on and 40 rotating with the shaft A⁶ which is rotatably mounted on the frame A.

A⁷ is a driving pulley connected to the

shaft A⁶ by any suitable driving means not shown and geared down to increase the available force for rotating the drum. A⁸ 55 is a holding link pressed yieldingly toward the drum by the spring A⁹ and engaging at its rear end the shaft A⁴ so that the lower edge of the concave is pressed yieldingly toward the crushing drum.

B, B are removable crushing mantles or jackets on the roll or drum. They have integral knobs or lugs B¹ adapted to assist in crushing the material. They are arranged in groups on the outer surface of 65 the mantle. Intermediate them are located a series of crushing tearing and feeding pins or teeth or cutters B². These cutters or teeth project outwardly beyond the periphery of the mantle and above the knobs 70 B¹. They have corrugated or serrated sides as indicated at B³. They are in engagement with the serrated surface B⁴ on the under sides of the hollow holding lugs B⁵.

Each pin is jammed into position against 75 such serrated surface by a wedge C which slidably engages the inner side of the pin. The wedge C is engaged by a curved cam surface C¹ on the locking lever C². This locking lever rolls in a pocket C³ having a 80 curved surface in engagement with the curved surface of the locking lever.

C⁴ is a stop lift in the locking lever which prevents too great inward movement of the wedge and C⁵ is an adjusting screw screw-threaded in the surface of the concave B and engages the tail of the lever or dog C² to rotate it in a counter-clockwise direction and jam the wedge against the pin or tooth. The lever itself is slotted or apertured to engage the end of the tooth. The function of the wedge is to make the device universal in its action so that different sizes of teeth, levers and pockets may coöperate 90 without interfering with the operation of the device. It may be as thick or as thin as necessary to enable a strong bite to be taken on the tooth and by this varying thickness it compensates for all the other inaccuracies of the other parts. The tooth 95 has a sharp point and this gradually wears down in operation and may be renewed and sharpened in the usual manner.

The concave as shown in Figs. 5, 6 and 7

is made up of a series of separate irregular curved surfaces. These surfaces it will be observed are tilted and the bounding lines converge as indicated so that they tend to feed or discharge the material to be crushed centrally from both sides toward parallel lines. The arrangement of the device is such that these parallel lines toward which the material is fed are the lines along which the teeth are located. The result is that the objects or particles fed into the machine as they pass down toward the crushing point are fed across the concaves toward the lines of action of the grabbing or feeding teeth. This effect may be obtained by any suitable arrangement of the surface of the concave. By my arrangement I insure that this cross feed will be taking place at all points and that most if not all of the material will be fed downwardly and inwardly toward the line of action of the feeding teeth before the concave zone is reached.

It will be evident that while I have shown in my drawings an operative device still many changes might be made both in size, shape and arrangement of parts without departing materially from the spirit of my invention, and I wish, therefore, that my drawings be regarded as in a sense diagrammatic.

The use and operation of my invention are as follows;—My device is, generally speaking, intended for the crushing of lumpy material. The knobs or teeth cast integral with the mantle will last almost indefinitely. When they finally wear out the mantle may be cast aside. The wear on the long teeth is hard and it is desirable to sharpen or remove them as the case may be. In any event, since they are removably mounted, it is only necessary to loosen up the set screw as shown when the levers will move to free the wedge which is then drawn out permitting the tooth bar to drop away from the serrated surface so that it can easily be withdrawn. When the bar is replaced the process is reversed in the usual manner.

I claim:

1. The combination with a supporting base member of a tooth bar having serrated sides and a tooth integral therewith, a pocket inside the base member partially containing the bar, and having a serrated wall and means for clamping the serrated portion of the tooth bar into engagement with the serrated pocket wall.

2. The combination with a supporting base member of a tooth bar having serrated sides and a tooth integral therewith, a pocket inside the base member partially containing the bar, and having a serrated wall and means for clamping the serrated portion of the tooth bar into engagement with the serrated pocket wall, said means comprising

a lever and means for rotating it and holding it in position.

3. The combination with a supporting base member of a tooth bar having serrated sides and a tooth integral therewith, a pocket inside the base member partially containing the bar, and having a serrated wall and means for clamping the serrated portion of the tooth bar into engagement with the serrated pocket wall, said means comprising a lever and means for rotating it and holding it in position, and a wedge interposed between the bar and the lever.

4. The combination with a supporting base member of a tooth bar having serrated sides and a tooth integral therewith, a pocket inside the base member partially containing the bar, and having a serrated wall and means for clamping the serrated portion of the tooth bar into engagement with the serrated pocket wall, said means comprising a lever and means for rotating it and holding it in position, and a wedge interposed between the bar and the lever, said lever being slotted intermediate its ends to permit the tooth bar to extend through it.

5. The combination with a supporting base member of a tooth bar having serrated sides and a tooth integral therewith, a pocket inside the base member partially containing the bar, and having a serrated wall and means for clamping the serrated portion of the tooth bar into engagement with the serrated pocket wall, said means comprising a lever and means for rotating it and holding it in position, and a wedge interposed between the bar and the lever, said lever being slotted intermediate its ends to permit the tooth bar to extend through it, and means carried by the lever within said slot for limiting the movement of the wedge toward the interior of the pocket.

6. The combination with a supporting base member of a tooth bar having serrated sides and a tooth integral therewith, a pocket inside the base member partially containing the bar, and having a serrated wall and means for clamping the serrated portion of the tooth bar into engagement with the serrated pocket wall, said means comprising a lever and means for rotating it and holding it in position, and a wedge interposed between the bar and the lever, and means carried by the lever for limiting the movement of the wedge toward the interior of the pocket.

7. The combination with a supporting base member of a tooth bar having serrated sides and a tooth integral therewith, a pocket inside the base member partially containing the bar, and having a serrated wall and means for clamping the serrated portion of the tooth bar into engagement with the serrated pocket wall, said means comprising a lever and means for rotating it

and holding it in position, said pocket having a curved wall, the lever having a curved bearing end in engagement with said wall, a set screw projecting inwardly through the 5 wall of the pocket into engagement with the free end of the lever to rotate it upon its curved bearing surface.

In testimony whereof, I affix my signature in the presence of two witnesses this 26th day of March, 1915.

AXEL G. J. RAPP.
